H. L. FERRIS

DOOR HOLDING ATTACHMENT

Filed Aug. 14, 1926

Inventor:

Henry L. Ferris,
Bydgoszcz, Chittenden, Vt.,
Attest,

UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

DOOR-HOLDING ATTACHMENT.

Application filed August 14, 1926. Serial No. 129,229.

This invention pertains particularly to a door-holding device which is adapted to automatically latch a door in the open position. The primary object of the invention is to provide an improved device of this character which can be manufactured at moderate cost, which can be readily applied to a door, and which will present a pleasing appearance and also will serve to hold the door staunchly and reliably in open position.

A feature of the present invention is the provision of a simple and effective device for enabling the latch to be released from the inner side of the door; and another feature of the invention is a novel keeper provided with a guide equipped at opposite ends with latch-shoulders, adapting the keeper to be used either as a right or left keeper.

20 Preferably, the improved attachment is connected with the door post and the door at about the horizontal center line of the door, and extending over the central hinge of the door, where such hinge is employed.

25 The invention is illustrated in its preferred embodiment in the accompanying drawing, in which—

Fig. 1 is a broken elevational view showing a fragment of a door-post and a door hingedly connected therewith, and showing also the improved door-holding device applied thereto; Fig. 2, a broken horizontal sectional view taken as indicated at line 2—2 on Fig. 1; Fig. 3, a fragmentary sectional view showing the door in open position; Fig. 4, a broken vertical sectional view taken as indicated at line 4 on Fig. 1; Fig. 5, a rear or inner elevational view of the elongated keeper employed, the view showing also a portion of the connecting rod employed; and Fig. 6, a broken vertical sectional view on an enlarged scale, the section being taken as indicated at line 6 on Fig. 1.

In the construction illustrated, A designates a post, or door-support; B designates a door connected with the member A by hinges B' (one shown); and C designates the improved door-holding attachment, having associated therewith a latch-releasing device C'.

The improved door-holding attachment is particularly useful in connection with garage doors, but may be employed in connection with swinging barn doors, or in other similar situations. It will be understood

that the door jamb, or door support, A, may be of any suitable construction, and that any desired number of hinges may be employed for carrying the door.

The door-holding attachment C comprises 60 a hinge member 1; a connecting rod 2 pivotally connected with said hinge member; and an elongated keeper 3 provided with a suitable guide interlockingly but slidably engaged by a head with which the connecting 65 rod 2 is equipped.

The hinge member 1 is provided with eyes 1^a separated by a space which accommodates freely the pivot portion 2^a of the connecting rod. A readily removable pintle 1^b extends 70 through the eyes 1^a and serves as a pivot for the rod 2. The connection at this point is loose enough to permit the opposite end of the rod 2 to drop the necessary amount to effect the latching connection. 75

The keeper 3 preferably is in the form of an elongated cast metal member, but may be stamped from sheet metal, if desired. This member is provided with a longitudinal embossment 3^a having a slot 3^b provided at its 80 ends with downwardly offset recesses 3^c. The walls 3^d of these recesses are preferably undercut, as shown in Figs. 1 and 5. The keeper 3 is secured, by means of screws 4, to the central cross member 5 of the door. 85

The keeper 3, as thus described, affords back of the front wall of the boss 3^a, a space or chamber 6 which is adapted to accommodate the flanged head 2^b with which the connecting rod 2 is provided. This head 90 is preferably formed by turning the end of the rod inwardly and upsetting the inwardly turned extremity to form the head. The eye 2^a of the rod may be passed readily through the slot 3^b from the rear of the keeper in making the connection between the keeper and the connecting rod. 95

In the operation of the device, the inwardly turned portion of the rod designated 2^c, is adapted to drop into the notch or recess 3^c at the far end of the keeper when the door is swung to the open position. On the other hand, the notch 3^c at the inner end of the keeper is so positioned that it cannot be engaged by the latch member when the door is in closed position. 105

The latch-releasing device C' preferably consists of a bell-crank lever journalled in a perforation in an eye 7 which is formed integrally with the end-portion of the keeper. 110

The eye 7 is duplicated at the two ends of the keeper for purpose of adapting the keeper to be used as a right and left keeper.

The bell-crank preferably is formed from a rod bent to afford a pivot-portion 8 and an arm 8^a. The pivot-portion extends through the eye 7 and a registering perforation 9 with which the door is provided. Normally, the arm 8^a depends vertically from the pivot, but when the pivot, or shaft, 8 is turned in the proper direction, the arm 8^a will engage the portion 2^c of the latch-link, or connecting-rod 2 and lift the latch-link from engagement with the notch 3^c. The shaft, or pivot, 8 has secured on its rear or inner end an actuating arm, or handle, 8^b. This arm is shown provided with a perforate hub-portion which slips onto the shaft and is removably secured in position by means of a set screw 10.

In the illustration given, the door-holding attachment is shown applied to a door located at the right of the door-support A. Obviously, however, the attachment may be applied where the door is located at the left of the door-support. In such case, the hinge 1 and connecting rod would be reversed, and the recesses 3^c at the left hand end of the keeper would become the operative recess adapted to engage the latch-link when the door is in open position. Also, it will be noted from Fig. 2 that the parts are so disposed that when the door is in the closed position, the latch-link 2 extends across and in close proximity to the eye-portion of the hinge B'.

Ordinarily, the leaf of the hinge 1 would be attached to the door-support A in such position that the end-edge of the leaf will bear against the rear edge of the fixed leaf of the hinge B' of the door.

The foregoing detailed description has been given for clearness of understanding only and no unnecessary limitations should be understood therefrom, but the appended claims should be construed as broadly as permissible in view of the prior art.

What I regard as new, and desire to secure by Letters Patent, is:

1. In combination with a door-support and a door hingedly connected therewith, a hinge-member secured to said door-support back of the pivot line of the door, a latch-rod pivotally connected at one end with said hinge-member and equipped at the other end with an inturned portion provided with a head, and an elongated keeper secured to said door, said keeper being provided with a guide having at opposite ends downwardly offset recesses affording latch-shoulders, the inturned portion of said latch-rod engaging said guide slot and being adapted to interlockingly engage the latch-shoulder at the remote end of said keeper when the door is in the open position while the latch-shoulder

at the inner end of the keeper is so positioned that it cannot be engaged by the latch-rod when the door is in closed position.

2. In combination with a door-support and a door hingedly connected therewith, a door-latch-rod pivotally connected with said door-support back of the pivot line of the door, an elongated keeper slidably and interlockingly engaged by said latch-rod, said keeper being provided at its remote end with a latch-shoulder adapted to be latchingly engaged by the latch-rod when the door is in open position, and a releasing device adapted to engage and lift said latch-rod, said releasing device having an operating member located at the inner side of the door.

3. A door-holding attachment adapted to secure a door in open position, comprising a hinge-member, a latch-rod having one end pivotally connected therewith and having its opposite end provided with an inturned portion equipped with a head, a keeper having an embossment provided with a guide slot having at its end a downwardly offset recess affording a large shoulder, said keeper being provided adjacent said recess with a pivot-perforation, and a latch-releasing device having a pivot-portion extending through said perforation and having an arm adapted to lift the latch-rod, said pivot-portion being equipped at its opposite end with an actuating arm.

4. A door-holding attachment comprising a hinge-member adapted to be secured to a door-support, said hinge-member being provided with vertical eyes spaced apart, a latch-rod having at one end an eye disposed between said first-named eyes, and at the other end an inturned portion equipped with a head, a vertical pintle connecting said eyes, and a keeper equipped with means for attachment to said door, said keeper having a longitudinal embossment provided with a guide slot having at opposite ends downwardly offset recesses affording latch-shoulders and said keeper being equipped at opposite ends with pivot-perforations, and a bell-crank lever comprising a pivot-portion, a latch-engaging arm, and an actuating arm, one of said arms being detachable and said bell-crank lever being adapted to be mounted in either one of said pivot-perforations.

5. In a device of the character set forth, an elongated keeper provided with a longitudinal embossment having a guide slot provided at opposite ends with downwardly offset recesses affording latch-shoulders, and a latch-rod having one end curved to form a pivot-eye and having the other end-portion bent inwardly and upset to form a head adapted to underlie said embossment while the inturned portion of the rod is movable in said guide slot, said latch-rod being insertable from the rear through said guide slot in assembling the parts.

6. In a device of the character set forth, an elongated keeper provided with a longitudinal embossment having a guide slot provided at opposite ends with downwardly offset recesses affording latch-shoulders, a latch-rod having one end curved to form a pivot-eye and having the other end-portion bent inwardly and upset to form a head adapted to underlie said embossment while the inturned portion of the rod is movable ¹⁵ in said guide slot, said latch-rod being insertable from the rear through said guide slot in assembling the parts, and means for lifting said latch-rod to release it from said recesses.

HENRY L. FERRIS.
